United States Patent Office.

ROBERT DEVEREUX, OF BUFFALO, NEW YORK.

Letters Patent No. 63,228, dated March 26, 1867.

IMPROVEMENT IN HAMMERS.

The Schedule referred to in these Letters Patent and making part of the same.

TO ALL WHOM IT MAY CONCERN:

Be it known that I, ROBERT DEVEREUX, of the city of Buffalo, county of Erie, and State of New York, have invented a certain new and improved "Hammer-Handle Fastening;" and I do hereby declare that the following is a full and exact description thereof, reference being had to the accompanying drawings, making a part of this specification, in which—

Figure I is a perspective view of my improved fastening.

Figure II is an elevation of the same as applied to a hammer.

Figure III is a section showing the connection thereof with the head of a hammer.

Figure IV is a perspective view of same.

The nature of this invention consists in making a metallic strap, which forms a dove-tail in the eye of the hammer and extends on to the handle on either side, and is riveted through the handle, as a means of fastening and strengthening the handle. This improvement is applicable to hammers of all kinds, sledges, hatchets, axes, and all similar tools.

Letters of like name and kind refer to like parts in each of the figures.

A A represent two straps, which form the connection of the handle to the head of the hammer, one being attached to each side of the handle, as shown in the drawings. They are both alike, and each is constructed as follows: The top of the strap is bent at right angles so as to form a flange, a^1 , which fits into a groove or recess made in the head of the hammer. A dove-tail is formed in the strap below this flange, as shown at a^2 , the length of which is equal to the length of the eye of the head, and corresponds exactly to a dove-tailed groove or recess formed in the eye on either side thereof. Rivet holes, a^3 , are made near the lower end of the strap for the purpose of riveting the two straps together by the rivets b passing through the handle. The lower end of the strap is made broader than the top part, forming upon either side a curved flange or wing, a^4 , which flanges clasp the handle and strengthen the same, thereby compensating for any weakness in the handle produced by the riveting. C represents the handle, and D the head of the hammer. The handle may be of common construction, but the head, when manufactured in combination with my improved fastening strap, is made as shown in the drawings. d^1 represents the eye or opening for the reception of the handle C. d^2 represents the recesses formed in the top of the head, upon each side of the eye, into which the flanges a^1 of the fastening strap are fitted, as shown in Figs. II and III. d^3 represents the dove-tailed grooves or recesses cut within and upon each side of the eye which correspond with and receive the dove-tailed part a^2 of the straps. It will be observed that the dove-tails a^2 and the flanges a^1 may be used separately, and still a good and sufficient fastening will be formed by either of them. When this improvement is to be applied to old tools, the heads of which are not provided with the dove-tailed grooves or recesses d^3 , the same may be dispensed with, and the flanges a^1 alone will be sufficient to hold the head firmly in place. The recesses d^2 may or may not, in that case, be filed into the top of the head if desired.

My improvement remedies the main difficulty experienced in the use of various tools, viz, the gradual working loose of the handle thereof, and furnishes a fastening therefor which cannot be surpassed by anything heretofore used for that purpose. The straps are removable, and in case one should break it can easily be replaced by a new one, or if the handle should break the same straps may be used for fastening a new handle to the tool in like manner.

What I claim as my invention, and desire to secure by Letters Patent, is—

Attaching a hammer or analogous tool to its handle, by means of the plate A, when said plate is constructed and applied to the handle as described, in combination with the recess d^3 in the eye of the hammer to receive the plate, substantially as set forth.

ROBERT DEVEREUX.
